[57] CLAIM

The ornamental design for a toy vehicle, substantially as shown and described.

DESCRIPTION

FIG. 1 is a right side elevational view of a toy vehicle showing my new design, the side opposite being substantially a mirror image;

FIG. 2 is a top plan view thereof;

FIG. 3 is a bottom plan view thereof;

FIG. 4 is a front elevational view thereof;

FIG. 5 is a rear elevational view thereof; and

FIG. 6 is a perspective view showing a front or jaw portion of the vehicle in an open position.

FIG. 1

FIG. 2

FIG. 3

FIG. 4

FIG. 5

FIG. 6
